UNITED STATES PATENT OFFICE.

HARRY C. MEYER, OF BUFFALO, NEW YORK, ASSIGNOR TO NIAGARA SILK MILLS, INC.,
OF NORTH TONAWANDA, NEW YORK, A CORPORATION OF NEW YORK.

PAPER BOX.

1,250,610.

Specification of Letters Patent. Patented Dec. 18, 1917.

Application filed July 16, 1915. Serial No. 40,234.

To all whom it may concern:

Be it known that I, HARRY C. MEYER, a citizen of the United States, and a resident of Buffalo, in the county of Erie and State 5 of New York, have invented a certain new and useful Paper Box, of which the following is a specification.

This invention has for its object the production of a paper or similar box particularly applicable for containing and displaying articles, as gloves, stockings and the like, and it consists in the novel features of construction hereinafter set forth and claimed.

In describing this invention, reference is 15 had to the accompanying drawings, in which like characters designate corresponding parts in all the views.

Figure 1 is a plan view of this box, the same being shown as open.

20 Fig. 2 is an isometric view of the box showing the same as closed.

Fig. 3 is an end view showing the locking tongue in operative position.

25 Fig. 4 is a plan of the blank from which the box is folded.

This box comprises, generally, a body 1, a cover 2, and a strip 3 connecting the body and the cover, and foldably connected to each of said parts 1, 2. The box is folded 30 from a blank A which is scored along marginal lines 4 and 5, and parallel transverse lines 6 located centrally of the blank midway between the lines 5 and being spaced apart the same distance as the marginal lines are spaced from the edges of the blank.

35 The side marginal lines 4 and 5 intersect and form blocks which are severed along the score lines 4, thereby forming flaps or blocks 7, and the intermediate transverse lines 6 and the marginal lines 4 intersect forming blocks 8 which divide the side margins set off by the lines 4 intermediate of the ends of said margins, the blocks 8 being severed along the score lines 4 from the ends of

40 the strip between the intermediate transverse lines 6, and along one of the lines 6 from the sections of the side margins on the cover 2 of the box, thereby forming flaps 9, this strip from which the flaps 9 are severed 45 50 constituting the connecting strip 3.

The opposing side margins are bent upwardly forming the side walls 10, 11 of the

body 1 and cover 2, respectively, and the flaps 7, 8 are bent inwardly, and the side margins 12, 13 bent upwardly against said flaps and secured thereto by an adhesive. The flaps 9 are also inturned and when the cover is closed, the strip 3 abuts against said inturned flaps 9.

When the cover is closed, the side walls of the cover lap the side walls of the body, and the cover is held closed or from accidental opening by suitable means consisting of a slot 14 formed in one of the side walls of the body 1 and a horizontally extending tongue 15 struck from the complementary wall of the cover, the tongue extending on opposite sides of the slot when the cover is closed, that is, the slot is located in a position opposite the middle of the tongue. 60 The tongue is here shown as formed by slitting the side or end wall of the cover along a line 16 parallel with the free edge of said wall 13, and then downwardly at an inclined angle to a point near, but not intersecting, 65 the edge of said wall 13 so that the tongue 15 is not completely severed at its free end, but is connected to the major part of the end wall 13 from which it is formed, by a narrow, easily-breakable neck 17. 70

When it is desired to lock the box, after the goods have been packed therein, the neck 17 is severed and the tongue 15 looped back and the end thereof is inserted in the slot 14. The fact that the end of the tongue is 85 cut on a bias, facilitates not only the breaking of the neck 17 at its free end, but the insertion of the tongue into the slot.

This box is particularly advantageous in that it is simple in construction and economical in manufacture. 90

What I claim is:—

A paper box comprising a body, and a cover folded up from a blank and flexibly connected together along contiguous ends of the body and the cover, the body and the cover having walls which lap at their free ends and one of the lapping walls being formed with a vertical slit and the other with a slit paralleling the free edge of the wall in which it is formed and with another slit extending from the former toward said free edge of said wall and terminating short of the same whereby a

tongue is connected at one end to the wall from which it is formed and is incompletely severed from said wall at its other end, substantially as and for the purpose described.

5 In testimony whereof I have hereunto signed my name in the presence of two attesting witnesses, at North Tonawanda, in

the county of Niagara, and State of New York, this 1st day of July, 1915.

HARRY C. MEYER.
